UNITED STATES PATENT OFFICE

BERNARD J. KOSHIOL, OF ST. CLOUD, MINNESOTA

RUNNING-BOARD LIGHT

Application filed May 31, 1929. Serial No. 367,554.

This invention relates to the broad class of illuminating devices, and has special reference to illuminating devices designed to be used upon and in connection with motor vehicles for the purpose of illuminating the running boards and the floor whenever a door is opened for the entrance or exit of a passenger.

An important object of the invention is to provide a safety light device mounted upon the running board shield or apron in such position as to throw light upon the running board and also upon the ground upon opening of the door or doors of the vehicle at the particular side in question, the real intention being that the light be duplicated, one at each running board with the respective lights controlled by opening or closing of the doors at that side of the vehicle.

Another object of the invention is to provide a safety light device which is energized by movement of switch devices mounted in the door jambs or posts and normally held in circuit breaking position by the doors when the latter are closed, means being provided whereby the switch or switches will be moved to closed or circuit completing position when a door or doors are opened.

Another object of the invention is to provide a novel switch device in the combination set forth which will be operated by opening or closing movement of the door of a vehicle.

Still another object is to provide a lamp device which may be mounted upon or formed integrally with the running board shield or apron and which will be very inconspicuous and which will therefore not in any way detract from the artistic and ornamental appearance of the vehicle.

An additional object is to provide a safety light and control mechanism therefor which will be very simple and inexpensive to make, easy to install, positive and automatic in operation, efficient and durable in service, and a general improvement in the art.

With the above and other objects and advantages in view, the invention preferably consists in the details of construction and

the arrangement and combination of parts to be hereinafter more fully described and claimed, and illustrated in the accompanying drawings, in which:—

Figure 1 is a side elevation of an automobile of the sedan type showing one side thereof and illustrating it as equipped with the safety light and a pair of switch devices adapted to be operated by the front and rear doors respectively. 55

Figure 2 is a fragmentary detail sectional view through a door and a portion of the door jamb or post engaged thereby showing the switch in side elevation. 60

Figure 3 is a detail sectional view through one of the circuit closing switches. 65

Figure 4 is an elevation looking at one edge of the door jamb and showing the switch device. 70

Figure 5 is a detail elevation of the safety light or lamp itself. 75

Figure 6 is a vertical sectional view therethrough taken on the line 6—6 of Figure 5. 80

Figure 7 is a diagram of the electrical circuit for either side of the car. 85

Referring more particularly to the drawings, the letter A designates an automobile including the usual body B, running board C, running board shield or apron D and doors E. All these and other elements are illustrated and described though the other features, such as wheels, fenders, hood, radiator and the like do not in any way enter into the invention. Furthermore, it is well known that every automobile is equipped with a storage battery, as is the one in the present instance, though this battery is not illustrated except in the diagram shown in Figure 7. 90

In carrying out the invention as applied, to a closed body of the coach type such as that illustrated, I provide a lamp indicated generally by the numeral 10 adapted and intended to be mounted upon the running board shield or apron D in such a position as to throw light upon the running board and also upon the ground on certain occasions or under certain conditions. The actual details of construction of this illuminating device are probably rather immaterial. 95

5 terial but it is here represented as comprising a base plate 11 to which is secured, by any desired means, a combined guard and reflector 12 which may be of any desired material but which is preferably constructed of metal. The guard 12 is of arcuate shape and is spaced away from the base plate 11, the edge being formed with a groove or other receiving means for a protective lens 10 or pane 13 as clearly indicated. Suitably mounted in any preferred manner upon the base 11 is a bracket 14 carrying a socket 15 of any ordinary or preferred variety within which is mounted an incandescent lamp or 15 bulb and which has terminal members 17 and 18 forming a part of a cable indicated at 19 brought out through a suitable insulating bushing 20 in the base plate 11. It is immaterial how this base plate 11 is actually 20 secured to the running board shield or apron D, and as a matter of fact, it may form an integral part thereof if such is preferred for any reason.

25 For controlling the energization of the incandescent lamp or bulb I provide a switch device in association with each door of the car or at least in connection with the doors at the side most used. Ordinarily it is the doors at the right side of the vehicle which 30 are commonly used more than the others and in case it is desired to reduce the cost of the installation it is apparent that the switches might be used only at this side. However, there is no limitation in this respect. These 35 switches are designated generally by the numeral 21 and are represented as located within the door jambs or posts F. The detailed construction of the switch may, of course, be varied within wide limits but I have shown it as of the spring pressed plunger type and made in the manner to be 40 described.

45 The switch device 21 is mounted on the door post or jamb F, as mentioned above and is accommodated within a recess 22. The switch device is represented as comprising an attaching plate 23 which is secured at the edge of the door post in such position as to cover the recess 22, attachment being 50 effected as by means of suitable bolts 24. This plate is of metal and suitably secured thereto is a tubular housing or sleeve 25, likewise of metal, and within which is slidably mounted a plunger 26 which projects through an opening 27 in the attaching plate so as to be engaged by the hinged edge of 55 the door.

60 The plunger 26 has a reduced stem 28 thereon slidable through the inner or closed end of the sleeve or housing, and surrounding this stem is a coil spring 29 which abuts against the plunger 26 and against the closed or inner end of the tubular guide or housing. The attaching plate 23 carries a block

or strip 30 of insulating material on which is mounted an angular contact 31 to which is connected a wire 32 for a purpose to be described. On the projecting end of the stem 28 is a head 33 adapted to engage 70 against the angular contact 31. As the parts 23, 25, 26, 28 and 33 are of metal and as the attaching plate 23 is secured to the metal casing F of the door post it is apparent that a ground connection is provided. 75 In addition to serving as contact means, the head 33 constitutes a stop for limiting the projection of the plunger 26 beyond the door post when the door is opened.

80 Referring to the diagram, Figure 7, the letter H designates the storage battery of the car which has one terminal grounded at I, as is customary. In installing my invention, I provide a conductor 34 connected with the other terminal of the storage battery and connected with the wire 17 which leads to the lamp 16, it being preferable that a fuse 35 be interposed in the connection for safety purposes. As mentioned above the heads 33 are grounded as shown at 36 in 90 the diagram. The wire 32 is connected by a wire 37 with the wire 18. As a matter of fact, the wires 18 and 37 may be the same but for the sake of clearness in the diagram they are represented as different. It will 95 also be observed that Figure 7 discloses two of the switches 21, one for each door at one side of the vehicle. It should be distinctly understood that if such is desired each door may be equipped with the switch device 100 at each side of the vehicle which would make four switches in all in case of a car of the sedan type or two switches in case of a car of the coach type. The number of switches is naturally immaterial inasmuch as the operation will be identically the same in every 105 instance.

Assuming that my light structure or lamp device has been mounted upon the running board shield or apron as illustrated and 110 that the switches have been installed within the door posts or jambs, it will be seen that when the doors are closed, the engagement of the hinged edges thereof with the plungers 26 of the switch devices will hold the 115 plungers in their innermost positions against the resistance of the spring 29 so that the heads 33 will be in spaced relation to the contacts 31. Clearly no current will then flow through the lamp or bulb 16. Whenever a door is opened, the disengagement of the hinged edge thereof with the associated 120 plunger 26 will permit the spring 29 to force the plunger out or project it beyond the attaching plate 23. When this occurs the 125 head 33 will engage against the angular contact 31 and provide the ground connection 36 whereupon current will flow from the storage battery H, through the wire 34, fuse 35, wire 17, filament of the lamp 16, wire 18, 130

wire 37, and wires 32, contact 31, head 33, stem 28 and to the ground. As the other terminal of the storage battery is also grounded it is obvious that there will be a complete circuit which will result in energization of the lamp or bulb 16 which will remain lighted as long as the door is open and which will throw light upon the running board and also upon the ground near the running board so that a passenger entering or alighting from the vehicle will see to obtain proper footing.

From the foregoing description and a study of the drawing it will be apparent that I have thus provided a very simply constructed and easily installed mechanism by means of which adequate illumination of the running board and ground nearby may be had whenever the door of a car is opened. This will be of great advantage in preventing passengers from missing their footing and slipping or stumbling upon the running board when getting into or out of a car. It is believed that the construction, operation and advantages will be readily understood without further explanation.

While I have shown and described the preferred embodiment of the invention, it should be understood that I reserve the right to make all such changes in the details of construction and the arrangement and combination of parts as will not depart from the spirit of the invention or the scope of the subjoined claim.

Having thus described the invention I claim:—

An electric lamp case comprising a base plate of substantially semi-circular shape and having a pair of arcuate shaped grooves, a substantially oval shape shield engaging one of said grooves and having a groove in the free edge thereof, a concave lens engaging in the groove of the shield and the other groove of the plate and having the convex face thereof projecting slightly beyond the lower edge of the shield, fastening means securing the shield to the plate and holding the lens within its respective grooves, and a bracket carried by said plate to support an electric lamp partially within the concave of the lens.

In testimony whereof I affix my signature.

BERNARD J. KÖSHIOL.
